GRINDING MACHINE

Frank M. Gertiser, Detroit, Mich., assignor to
Cincinnati Grinders Incorporated, Cincinnati,
Ohio, a corporation of Ohio

Application March 1, 1933, Serial No. 659,215

17 Claims. (Cl. 51—103)

This invention relates to improvements in machine tools and especially to improvements in grinding machines of the centerless type.

An object of this invention is the provision of 5 an improved grinding machine for producing irregular shaped work pieces, particularly relieved or oval pistons, as employed in internal combustion engines.

Another object of the invention is the provision 10 of a simple machine that will not readily become out of order and yet will produce the work pieces above indicated in an expeditious manner and within accurate limits.

A further object of the invention is the provision 15 of a machine of this type so designed as to insure successive work pieces being identical in all respects.

A still further object of the invention is the provision of a grinding machine for relieving internal combustion engine pistons that is automatic or semi-automatic in its functioning, requiring the operator only to manually replace the work and initiate the cycle of operation.

Other objects and advantages of the present 25 invention should be readily apparent by reference to the following specification considered in conjunction with the accompanying drawings, forming a part thereof, and it is to be understood that any modifications may be made in the exact 30 structural details there shown and described, within the scope of the appended claims, without departing from or exceeding the spirit of the invention.

In the drawings:

Figure 1 is a front elevation of a grinding machine embodying the improvements of this invention.

Figure 2 is an end elevational view of the machine shown in Figure 1, and as seen from line 40 2—2 on Figure 1.

Figure 3 is a horizontal sectional view taken substantially on the line 3—3 of Figure 1.

Figure 4 is a fragmentary developed plan of a clutch employed in the driving train and forming 45 a detail of the invention.

Figure 5 is a fragmentary sectional view taken on line 5—5 of Figure 3.

Figure 6 is a vertical fragmentary sectional view taken through the throat of the grinding machine 50 taken on line 6—6 of Figure 3.

Figure 7 is a sectional view through the arbor which rotates the work and as seen particularly from line 7—7 on Figure 3.

Figure 8 is a fragmentary sectional view taken 55 on line 8—8 of Figure 3.

Figure 9 is a sectional view through the feed and cycle control mechanism, as seen from line 9—9 on Figure 1, a sectional view of the prime mover therefore being omitted.

Figure 10 is a view taken on line 10—10 of Figure 5 9 illustrating the control cam in elevation.

Figure 11 is a view at right angles to Figure 10, as seen from line 11—11 on Figure 10.

Figure 12 is a horizontal sectional view through the pressure roller as seen from line 12—12 on 10 Figure 6 and forming a detail of the invention.

Figure 13 is a fragmentary sectional view through the stopping mechanism as seen from line 13—13 on Figure 1.

Figure 14 is a view partly in section and partly 15 in elevation taken on line 14—14 of Figure 9.

Figure 15 is an enlarged diagrammatic development of the work rotation control and feeding mechanism.

Figure 16 is a diagrammatic view of an electrical 20 circuit for controlling the machine cycle.

Throughout the several views of the drawings similar reference characters are employed to denote the same or similar parts.

A machine of this invention may comprise a 25 bed 20 having rising therefrom a pedestal bearing 21 in which is journaled a spindle 22 for a grinding wheel 23. The spindle 22 and grinding wheel 23 are adapted to be rotated at a high rate of speed in a clockwise direction. The bearing 21 30 terminates in a hood that encloses a grinding wheel 23 from which hood projects a support 24 for a truing mechanism 25 adapted to be actuated across the face of the wheel 23 for truing and sharpening same.

The bed 20 is further provided on its upper 35 surface with a dove-tailed guide 26 received in a correspondingly shaped guideway formed in a slide 27. The slide 27 is in turn provided on its upper surface with a dove-tailed guide 28 likewise received in a correspondingly shaped guideway formed on an upper slide 29. The slide 29 is in effect a housing which encloses mechanism for controlling the rotation of the work and for effecting the relative feed thereof toward and 45 from the grinding wheel.

The work 30 is, as was above noted, a piston as employed in internal combustion engines and is adapted to have the skirt thereof at diametrical points relieved or undercut leaving the remaining 50 portion of the piston cylindrical. The work, as shown in Figures 1 and 6, is supported by a pair of work rest blades 31 and 32 respectively secured in slots 33 and 34 formed in a work rest block or bracket 35 secured to the inner edge of 55

the lower slide 27. The blades 31 and 32 are each provided with an inclined supporting surface 36 inclining toward one another for thereby forming a work receiving trough in which the work is deposited while in contact with the operative face of the grinding wheel.

The work is backed up at a point substantially diametrical to that contacted by the grinding wheel with a rotatable feed wheel 37 which in effect is a multiple lobed cam which will be described in detail later. The wheel or cam 37 is secured to a spindle 38 journaled in anti-friction bearings 39 and 40 supported by bearing bosses 41 and 42 of the housing 43 secured in any desirable manner to the slide or housing 29. The spindle 38 is adapted to be rotated at a relatively slow rate of speed in a clockwise direction and in timed relation with the rotation of the work. In fact, the wheel or cam 37 and the work 30 are rotated at the same peripheral speed whereby they are in effect geared to one another for a purpose that will later appear.

In order to set up the machine for different sizes or kinds of work the upper and lower slides 27 and 29 are adapted to be independently actuated, while during actual practice they are simultaneously shifted. For this purpose there is provided a clamp 44, see Figure 1, whereby the slides are clamped to one another for unitary movement while the lower slide carries clamps 45 which when operated to clamping position secure the said lower slide against movement, while permitting independent movement of the upper slide relative thereto. In order to adjust these slides 35 whether independently or as a unit relative to the bed, the upper slide or housing 29 has secured therein a sleeve nut 46, see Figure 3, that meshes with the screw threads 47 of an adjusting screw 48. The screw 48 extends through and beyond the automatic feed and control mechanism enclosed within housing 49 secured to a projecting lug or ledge 50 of the bed 20. For rotating the screw 48 it has secured to its projecting end a pilot or hand wheel 51.

The work 30 and backing up and feeding wheel or cam 37 are rotated from the same source, which includes a prime mover (not shown) driving through a variable speed control mechanism enclosed within the housing or box 52, see Figures 50 1 and 2, let into one end of the bed 20. The change speed gears being actuated by the lever 53 which projects from the housing or box 52. The mechanism enclosed within the box 52 may be of any well-known type and terminates in the 55 final driven shaft 54 which projects beyond the bed and carries a sprocket 55 about which is trained a sprocket chain 56. The sprocket chain 56 extends upwardly along the rear of the bed 20 and is enclosed within a housing or guard 57 and is in turn trained about the sprocket 58 keyed or otherwise secured to a shaft 59, journaled in the slide or housing 29. Also keyed or otherwise secured to the shaft 59 is a pair of different sized pinions or gears 60 and 61, the former or larger gear meshing with a gear 62 keyed to a transverse shaft 63, while the latter or smaller gear meshes with a larger gear 64 loosely journaled on the said shaft 63. From this it will be seen that the shaft 63 is rotated at a 65 faster rate of speed than the gear 64. Keyed or otherwise secured to the gear 64 for rotation therewith is a chain sprocket 65 about which is trained a chain 66 in turn trained about a larger sprocket 67 keyed or otherwise secured to the spindle 38 intermediate the bearings 39 and 40.

The transverse shaft 63 is journaled in the housing or slide 29 and has keyed or otherwise secured to its other end a bevel gear 68 meshing with a bevel gear 69 loosely encircling a longitudinal shaft 70. The gear 69 has projecting from it a sleeve 71 on the end of which is formed a single clutch tooth 72. The clutch tooth 72 is adapted to engage a similar clutch tooth 73 on a clutch member 74 keyed to the longitudinal shaft for sliding movement relative thereto. The 10 operation of the clutch will be described in detail later.

The shaft 70 is in two parts and has telescoping therewith the second part 70a. The shaft 70a is journaled in a bracket 75 secured to and 15 carried by the work rest block 35 and the shaft has secured to its end interiorly of the bracket 75 a bevel pinion 76 meshing with a complementary bevel gear 77 keyed or otherwise secured to the arbor 78. The arbor 78 is journaled in the 20 bracket 75 and projects forwardly into the grinding throat formed by the proximate portions of the grinding wheel and backing up or cam wheel 37. The inner end of the arbor 78 is provided with a forked member 79 having the fingers 25 thereof encircling a dummy wrist pin 80 passing through the wrist pin holes or bores in the work 30.

From the foregoing it will be seen that the spindle 38 is rotated at a lower speed or R. P. M. 30 than the arbor 78, but due to the ratios between the several gears and sprockets, the work and backing up or cam wheel are in fact rotated at the same peripheral speed, although at different R. P. M.'s. This ratio is such that the work 35 makes three revolutions to but a single revolution of the backing up or cam wheel 37.

As will be seen in exaggerated form from Figure 15, the cam wheel has in effect six lobes 81a, 81b, 81c, 81d, 81e, and 81f between each pair of which is a receding low portion 82a, 82b, 82c, 82d, 82e, and 82f. From this it will be seen that two of the lobes engage with the work during each rotation thereof since the said lobes are equally spaced around the periphery of the wheel. From 45 this it will be evident that each lobe as it engages the work will actuate it toward the grinding wheel while as the low portions come into play the work will be permitted to fall away from the grinding wheel and thereby relieve the work at 50 the desired diametrical points or portions.

As was mentioned above, the work as a whole is automatically brought into operative engagement with the grinding wheel for which purpose the housing or casing 49 encloses the feed and control mechanism. This mechanism comprises a bearing 83 formed in the casing 49 through which is axially shiftable a slide block 84. The slide block 84 is secured to a reduced portion 85 of the adjusting screw 48 and said slide block 60 has pivoted to it one end of a pair of pitmans or links 86, the other ends of which are pivoted at 87 to one arm 88 of a bell crank 89. The bell crank 89 is pivoted at the juncture of its arms to one wall 90 of the housing 49 and to a web 91 projecting upwardly from the base of the housing 49. The other arm 92 of the bell crank 89 carries a block 93 for a roller or cam follower 94 received in cam track 95 of face cam 96. The cam track 95 is provided with a rapid rise for 70 rapidly actuating the slides toward the grinding wheel to cause initial contact between the work and the wheel whereupon a slow rise of the cam track is employed for slowly feeding the work into the grinding wheel. This is followed by a 75

substantially concentric portion of the cam track to permit sparking out between the work and wheel whereupon a rapid decline is encountered for rapidly retracting the work from the wheel. It is while in the retracted position that the work is replaced or changed.

The cam 96 is secured to one end of a shaft 97 rotatably journaled in a bearing provided by the housing 49 and the shaft has secured to it near its other end a worm wheel 98 meshing with a worm 99 formed on or secured to a worm shaft 100 disposed transversely of the housing 49. Secured to the under surface of the housing 49 is a motor or prime mover 101 belted or geared as by a transmission within the guard 102 to the extreme end of the worm shaft 100.

The parts are adapted to make one complete cycle and then stop. For this reason a limit switch is included in the electrical circuit controlling the prime mover 101. The switch is enclosed within a housing or guard 103, see Figures 9 and 14, from which projects the switch actuating stem 104. The stem 104 is adapted to be engaged by a cam lug 105 formed on the plate 106 secured in any desirable manner to the cam shaft 97 for rotation therewith. From this it will be seen that each revolution of the cam shaft 97 actuates the switch plunger 104 for closing the stopping switch and thereby breaking the circuit to the motor 101 and stopping the movement thereof. These parts come into play during the time that the feed cam 96 is in position for completely retracting the work and slides from the grinding wheel.

The electrical circuit for the motor 101 is shown in Figure 16 and illustrates the main line wires 131 and 138 connected with the motor 101 by wires 139 and 140. Included in the wires 139 and 140 is a magnetic switch 141 having associated therewith the magnetic latch 142 for latching the switch in a closed position. A push button control station is also included in the circuit and comprises a normally open starting switch 143 and the normally closed stopping switch 144. The stopping switch 144 might be termed the emergency stop switch as it is only used in case of emergency since the cycle is ordinarily broken by the limit switch 104. In actual practice the push button control station is mounted on the front face of the machine bed and is contained in a casing or housing 145 to which is pivoted a lever 146 in contact with the starting switch 143. The lever 146 terminates in knob or plate 147 disposed in position for engagement by the operator's knee, thereby leaving his hands free for replacement of the work on the work arbor.

Just prior to the stopping of the motor or prime mover 101 the work drive is stopped for thereby stopping the arbor 78 to permit a replacement of the work thereon. As suggested above this stop includes the clutch member 74, shown in developed plan in Figure 4, which has the interrupted cam groove 107 into which the nose 108 of clutch shifter shaft 109 is adapted to be injected. The shaft 109 is in two parts suitably connected by means of a pin and slot 110a and between the two parts of the shaft is a spring 110. The second part 109a of the shaft is provided with a notch receiving the ball end 111 of a lever 112 pivoted intermediate its ends at 113 in the housing or slide 29. The lever 112 has its other end ball shaped, as at 114, which is received in a notch in a transverse rod 115 which extends along the right hand end of the machine and

terminates in the short rack 116, see Figure 13. Meshing with the rack 116 is a pinion 117 keyed or otherwise secured to a shaft 118 projecting outwardly from the casing 49. The shaft 118 is journaled in one wall of this casing as well as in a lug 119 projecting from the side of the casing. Secured in any suitable manner to the shaft 118 is a cam plate or wheel 120 having a single tooth 121 adapted to engage the hooked end 122 of a slide rod 123 slidably transversely of the housing 10 or casing 49 interiorly thereof. An arm 124 is provided interiorly of the casing 49, being pivoted at 125 to a lug 126 at one end and having a pin and slot connection 127 at its other end with the hooked slide rod 123. Intermediate its ends the arm 124 has projecting from it a lug 128 adapted to engage with cam lug 129 on the rear face of the feed control cam 96. The face or cam track 95 is so related to the cam lug 129 that after the work has been retracted from the grinding wheel 20 and before the switch plunger 104 is actuated, the arm 128 is engaged by the lug 129 for shifting the bar 115 and causing the clutch shifter to engage the cam groove 107 and disengage the clutch from the shaft 70 and thereby stop the 25 rotation of the work.

It should be noted that since the clutch member 74 has but a single tooth 73 and the co-operating clutch or gear 71 has also a single clutch tooth, the arbor 78 will be rotated only when the parts 30 are in a definite relationship so that successive work pieces are produced with the relieved portions in the same relative positions with the remaining parts thereof.

In order to hold the work on the work rest 35 blades and in proper contact with the wheel 37 the work rest block has projecting upwardly therefrom a bracket 130 to which is secured a block 131 by means of a stud 132 which passes through a perforation formed in the bracket 130. Passing through the block 131 is a sleeve 133 enclosing a spring pressed plunger 134. The plunger 134 has at its lower end a clevice 135 rotatably supporting a roller 136 adapted to contact with the work on one side of the center thereof in such a 45 manner as to yieldably urge the work away from the grinding wheel into contact with the blades 31 and 32 and the wheel or cam 37.

The operation of this mechanism is as follows: The arbor and slides are in a retracted position 50 with the arbor stationary, that is not rotating. The operator places a work piece on the arbor and disposes the driving pin carried thereby between the fingers of the driving fork on the end of the arbor. He then engages the knob or plate 147 of 55 the lever 146 with his knee, completing the electric circuit to the magnetic switch 141 and thereby starting the rotation of the motor 101. As soon as this circuit is complete the magnetic latch drops into place and retains the switch in a closed position so that upon release of pressure on the knob 147, the starting switch then opens. The rotation of the motor 101 rotates the cam 96, first causing the lug 129 on the rear thereof to release the lever 124 so that the clutch ejector rod 109—65 109a is withdrawn from the clutch member 74 thereby permitting its single tooth to be placed in the path of the single tooth of the co-operating clutch member, here shown as the bevel gear. About the time the two teeth are in engagement, 70 the cam 96 has reached the point for shifting the slides and work toward the grinding wheel. Since the backing up or cam member is constantly rotating, the work is therefore in addition being shifted toward and from the grinding wheel an 75

amount equal to the lobes on said cam and backing member. This continues until the cam 96 reaches its portion for retracting the work, at which time the said work is reduced to the desired size and contour.

As soon as the work has been retracted from the grinding wheel, the clutch ejector rod is inserted in the cam groove therein for retracting the clutch and breaking the drive to the work 10 whereupon the rotation thereof stops. As soon as the work has stopped the limit switch 104 is actuated for breaking the circuit to the magnetic switch and thereby opening said switch and stopping the rotation of the motor, thereby stopping the slides and work in their retracted positions. The operator then replaces the work whereupon he again engages the lever 146 with his knee and initiates a new cycle.

To compensate for inevitable wheel wear the 20 hand or pilot wheel 51 is periodically advanced and thereby insuring successive work pieces being reduced to the same size and contour.

It is believed that the operation of the improved 25 machine for producing formed work pieces such as relieved pistons will be readily apparent from the foregoing description. It is to be noted, however, that the mechanism is not to be restricted to the manufacture of relieved pistons, but has equal application to the forming or production of 30 cams and other irregular objects.

What is claimed is:

1. In a grinding machine of the class described 35 the combination of a bed, a grinding wheel rotatably mounted thereon, means adjacent the grinding wheel for peripherally supporting a work piece while in contact with the wheel, means for rotating the work while supported, and contoured rotatable means diametrically opposed to the grinding wheel and peripherally engaging the work, said contoured means having successive 40 peripheral elevations and depressions effective against the work whereby the work is variably urged into operative engagement with the grinding wheel.

2. In a grinding machine of the class described 45 the combination of a bed, a grinding wheel rotatably mounted thereon, means adjacent the grinding wheel for peripherally supporting a work piece while in contact with the wheel, means for rotating the work while supported, contoured rotatable means diametrically opposed to the 50 grinding wheel and peripherally engaging the work, said contoured means having successive peripheral elevations and depressions effective against the work whereby the work is variably urged into operative engagement with the grinding wheel, and means synchronizing the rotation 55 of the work and contoured means.

3. In a grinding machine of the class described 60 for producing successive work pieces to the same irregular contour the combination of a pair of opposed members, one of which is a grinding element operable at a grinding rate of speed and the other a backing up member of irregular contour, said members forming between them a grinding 65 throat in which the work is disposed, a work support sub-tending the grinding throat for peripherally supporting the work, and means for driving the work and irregular backing up member at the same peripheral speeds for effecting an intermittent feed of the work with respect to the grinding wheel.

4. In a grinding machine of the class described 70 for producing successive work pieces to the same irregular contour the combination of a pair of

opposed members, one of which is a grinding element operable at a grinding rate of speed and the other a backing up member of irregular contour, said members forming between them a grinding throat in which the work is disposed, a work 5 support sub-tending the grinding throat for peripherally supporting the work, means for driving the work and irregular backing up member at the same peripheral speeds for effecting an intermittent feed of the work with respect to the 10 grinding wheel, and means for supporting one of said members together with the work rest blade for unitary movement for operatively associating the work with the other of said members.

5. In a grinding machine of the class described 15 for producing successive work pieces to the same irregular contour the combination of a pair of opposed members, one of which is a grinding element operable at a grinding rate of speed and the other a backing up member of irregular contour, said members forming between them a grinding throat in which the work is disposed, a work support sub-tending the grinding throat for peripherally supporting the work, means for driving the work and irregular backing up member at 20 the same peripheral speeds for effecting an intermittent feed of the work with respect to the grinding wheel, and means supporting one of said members together with the work rest blade for unitary movement for operatively associating the work with the other of said members, said means comprising a cam, and power means for rotating the cam.

6. In a grinding machine of the class described 25 for producing successive work pieces to the same irregular contour the combination of a pair of opposed members, one of which is a grinding element operable at a grinding rate of speed and the other a backing up member of irregular contour, said members forming between them a grinding 30 throat in which the work is disposed, a work support sub-tending the grinding throat for peripherally supporting the work, means for driving the work and irregular backing up member at the same peripheral speeds for effecting an intermittent feed of the work with respect to the grinding wheel, and means supporting one of said members together with the work rest blade for unitary movement for operatively associating the work with the other of said members, said means comprising a cam, power means for rotating the cam, and means for interrupting the power means for the cam at the conclusion of a single cycle.

7. In a grinding machine of the class described 35 the combination of a pair of opposed elements rotatable about axes disposed in parallel planes, one of said elements being a grinding wheel and the other a work backing member and one of said parts being irregular in contour for intermittently effecting a relative axial approach of the work 40 and grinding wheel for thereby providing an irregular surface on the work, a work support sub-tending the grinding throat and peripherally supporting a work piece while contacting the grinding and backing up elements, and yieldable means 45 operable on the work for holding same against the peripheral support and one of the elements.

8. In a work supporting and feeding mechanism for use with grinding machines the combination of a pair of super-imposed slides, a work 50 support on one of said slides for peripherally supporting a work piece, a backing up member in the nature of a multi-lobed cam on the second slide, said work and backing up cam being of different diameters, and means for rotating said backing 55

up member and work at the same peripheral speed and in timed relation whereby successive work pieces have their surfaces similarly formed.

9. In a work supporting and feeding mechanism for use with grinding machines the combination of a pair of super-imposed slides, a work support on one of said slides for peripherally supporting a work piece, a backing up member in the nature of a multi-lobed cam on the second slide, said work and backing up cam being of different diameters, and means for rotating said backing up member and work at the same peripheral speed and in timed relation whereby successive work pieces have their surfaces similarly formed, said means including an arbor for the work mounted on one of the slides, a spindle on the second slide for the backing up member, and transmission means including speed up gearing for rotating the spindle and arbor at different speeds.

10. In a work supporting and feeding mechanism for use with grinding machines the combination of a pair of super-imposed slides, a work support on one of said slides for peripherally supporting a work piece, a backing up member in the nature of a multi-lobed cam on the second slide, said work and backing up cam being of different diameters, and means for rotating said backing up member and work at the same peripheral speed and in timed relation whereby successive work pieces have their surfaces similarly formed, said means including an arbor for the work mounted on one of the slides, a spindle on the second slide for the backing up member, transmission means including speed up gearing for rotating the spindle and arbor at different speeds, and a common source of power for the transmission, arbor and spindle.

11. In a work supporting and feeding mechanism for use with grinding machines the combination of a pair of super-imposed slides, a work support on one of said slides for peripherally supporting a work piece, a backing up member in the nature of a multi-lobed cam on the second slide, said work and backing up cam being of different diameters, means for rotating said backing up member and work at the same peripheral speed and in timed relation whereby successive work pieces have their surfaces similarly formed, and means for cyclically effecting a relative approach and retraction of the work and wheel one with respect to the other to operatively associate the work and wheel to effect a stock removal from the work and dis-associate same to permit a re-placement thereof.

12. In a work supporting and feeding mechanism for use with grinding machines, the combination of a pair of super-imposed slides, a work support on one of said slides for peripherally supporting a work piece, a backing up member in the nature of a multi-lobed cam on the second slide, said work and backing up cam being of different diameters, means for rotating said backing up member and work at the same peripheral speed and in timed relation whereby successive work pieces have their surfaces similarly formed, means for cyclically effecting a relative approach and retraction of the work and wheel one with respect to the other to operatively associate the work and wheel to effect a stock removal from the work and dis-associate same to permit a replacement thereof, and means for stopping said means at the completion of each cycle.

13. In a work supporting and feeding mech-

anism for use with grinding machines the combination with a grinding wheel, of a pair of super-imposed slides, a work support on one of said slides for peripherally supporting a work piece, a backing up member in the nature of a multi-lobed cam on the second slide, said work and backing up cam being of different diameters, means for rotating said backing up member and work at the same peripheral speed and in timed relation whereby successive work pieces have their surfaces similarly formed, means for cyclically effecting a relative approach and retraction of the work and wheel one with respect to the other to operatively associate the work and wheel to effect a stock removal from the work and dis-associate same to permit a replacement thereof, means for stopping said means at the completion of each cycle, and means independent of said stopping means for again initiating the cycle.

14. A grinding machine of the class described for producing relieved pistons for internal combustion engines the combination of a bed, a grinding wheel rotatably mounted thereon, a work support adjacent the grinding wheel comprising a pair of supporting blades each having an inclined supporting surface inclining toward one another and forming a trough in which the piston is peripherally supported, a multi-lobed cam opposed to the grinding wheel for intermittently shifting the piston into the grinding wheel, means for positively rotating the piston and cam in timed relation, a slide on the bed for supporting the work support and cam, and means for actuating the slide relative to the bed for operatively associating and dis-associating the work and grinding wheel.

15. A grinding machine for the purpose described including a bed, a work rest rising from the bed for peripheral engagement with the work to be ground, a grinding wheel disposed at one side of the work rest for operative engagement with the work piece when mounted thereon, a rotatable backing up member in the form of a multi-lobed cam disposed at the opposite side of the work rest for engagement with the work piece whereby the work piece is variably actuated on its rest in the direction of the grinding wheel in accordance with the contour of the multi-lobed cam, a positively driven arbor member, and flexible drive connections carried by the arbor for engagement with the work piece to effect a predetermined rate of rotation of the work piece while permitting its free floating movement on the support as determined by the lobes of the cam.

16. A grinding machine for the purpose described including a bed, a work rest rising from the bed for peripheral engagement with the work to be ground, a grinding wheel disposed at one side of the work rest for operative engagement with the work piece when mounted thereon, a rotatable backing up member in the form of a multi-lobed cam disposed at the opposite side of the work rest for engagement with the work piece whereby the work piece is variably actuated on its rest in the direction of the grinding wheel in accordance with the contour of the multi-lobed cam, a positively driven arbor member, flexible drive connections carried by the arbor for engagement with the work piece to effect a predetermined rate of rotation of the work piece while permitting its free floating movement on the support as determined by the lobes of the cam, and a transmission coupling the arbor and

cam for insuring synchronous rotation thereof in predetermined ratio.

17. A grinding machine for the purpose described including a bed, a work rest rising from the bed for peripheral engagement with the work to be ground, a grinding wheel disposed at one side of the work rest for operative engagement with the work piece when mounted thereon, a rotatable backing up member in the form of a 10 multi-lobed cam disposed at the opposite side of the work rest for engagement with the work piece whereby the work piece is variably actuated on its rest in the direction of the grinding wheel in accordance with the contour of the 15 multi-lobed cam, a positively driven arbor mem-

ber, flexible drive connections carried by the arbor for engagement with the work piece to effect a predetermined rate of rotation of the work piece while permitting its free floating movement on the support as determined by the lobes 5 of the cam, a transmission coupling the arbor and cam for insuring synchronous rotation thereof in predetermined ratio, a clutch member shiftable to interrupt the coupled drive between the cam and arbor, and means effective 10 to re-establish the drive connection with a predetermined relationship between arbor and cam, substantially as and for the purpose described.

FRANK M. GERTISER. 15
